(57) **CLAIM**

I claim the ornamental design for a bicycle frame subassembly, as shown and described.

DESCRIPTION

FIG. 1 is a perspective view of a bicycle frame subassembly showing my design from the left side; and,

FIG. 2 is a right side perspective view thereof.

The broken line drawings of the pedals in FIGS. 1 to 2 are for illustrative purposes only and form no part of the claimed design.

1 Claim, 1 Drawing Sheet

FIG. 1

FIG. 2
